E. W. HAWKINS

BABY CARRIER

Filed Oct. 1, 1923

Patented Mar. 17, 1925.

1,530,116

UNITED STATES PATENT OFFICE.

ERROL W. HAWKINS, OF LONG BEACH, CALIFORNIA.

BABY CARRIER.

Application filed October 1, 1923. Serial No. 665,947.

To all whom it may concern:

Be it known that I, ERROL W. HAWKINS, a citizen of the United States, and a resident of Long Beach, Los Angeles County, California, have invented certain new and useful Improvements in Baby Carriers, of which the following is a specification.

My invention relates to baby carriers; and while I have so designated it in this specification and illustrated it in the drawings it is to be understood that it can be used for carrying any articles whatsoever for which it is suitable.

Among the salient objects of my invention are,—to provide a simple frame member with carrier therein to receive the baby, or articles, to be carried, said frame member being foldable to various forms, whereby said device will serve as a cradle-like device, or as a basket-like device to be carried at the side, much as a suit case is carried, thus eliminating danger in crossing streets, and also eliminating jarring in crossing railroad tracks, or other rough places, because the device can be bodily lifted, or partially lifted, as may be necessary, so as to permit the minimum amount of shaking of the device over the rough course of travel; to provide a device of the character referred to which can be folded into small compass to be packed or carried from place to place; to provide a device which can be used by a baby for self propelling itself over the floor, its legs being placed through suitable openings in the carrier in the frame; and in general, to provide a simple, efficient, convenient and comparatively inexpensive carrier of the character referred to.

In order to fully explain my invention, I have shown one practical embodiment thereof on the accompanying sheet of drawings, which I will now describe. In the drawings,—

Figure 1 shows my device adjusted for service as a cradle and movable;

Figure 2 shows the device adjusted to be carried at the side, or partly carried and partly moved on its castors;

Figure 3 shows the device adjusted to a form to be pushed with one end running on the walk or floor, the castors being adjusted for this purpose;

Figure 4 is a perspective view of a detachable castor; and

Figure 5 is an enlarged view of one of the frame joints with holding means for hold-

ing the frame members to different adjusted positions.

Referring now more in detail to the drawings, frame members, 1 and 2, are hinged together with a hinge member 3, as shown in Fig. 5, said hinge member being provided with a plurality of radial slots, as 6, to receive the dog, 7, normally held closed by means of a spring, 8. Two pairs of said frame members, 1 and 2, and said hinge 3, are provided, with a carrier frame, 9, pivotally supported therebetween, as on ears 10, on the pivot pin 11, of the hinge member 3. The lower ends of said frame members 1 and 2, telescope into the bent ends, 12^a, 12^a, and 13^a, 13^a, of two long frame members, 12 and 13, with slot and button means for holding said telescoping parts in adjusted positions, as indicated at 14. Any suitable means can be used for holding said telescoping parts in adjusted position.

An arm, 15, is extended from the frame member 13, said arm being in two parts, telescoping and adapted to be locked in adjusted positions by a thumb bolt, 16, as indicated. Said arm is rigidly attached to the frame member 13, and is provided at its inner end with a castor, 17. It will be noted that said arm 15 is set at such an angle that it will operate to hold the frame members 2, 2, and the carrier frame 9, in the position indicated in Fig. 2, even when frame members 1, 1 and 12 are raised to a position over the frame members 2, 2, and 13. The frame member 12, is provided with a hand grip, 18, for carrying the device in the hand at the side, when raised or adjusted to the form shown in Fig. 2.

The carrier frame 9, is provided with a canvas carrier, 19, but this can be of any suitable material. I have shown it provided with leg holes, 19^a, with a cover flap, 20, whereby the flap can be removed and with the device set up as indicated in Fig. 1, the child can be placed therein with its legs through the leg holes, 19^a, and can push the device about on the floor. The cover flap 20, can be made to button on the lower end of the carrier frame 9, as indicated.

In Fig. 4, I have shown a form of detachable castor, having the clamps 21 and 22, adapted to be secured together by the thumb screw, 23, with the castor, 24, swiveled thereto. The other castors, as 25, are secured to the frame members in any suit-

able manner, and in the proper angles to serve the purposes as illustrated.

The use and operation of the carrier as here illustrated may be briefly described as follows:

With the device adjusted and set up as indicated in Fig. 1, it can be used as a cradle in the home, or on the porch, or elsewhere, and at the same time it can be easily rolled from place to place or moved back and forth as a carriage is moved, all as will be readily understood.

The device can be folded as in Fig. 2, and will stand because of the extension 15, which can be extended to the desired or necessary length to form a tripod support, the frame member 12 being raised to the position indicated in dotted lines, that is, to a horizontal position, or it can be raised upwardly to the inclined position indicated in full lines and still allow the extension 15 to rest on the floor, or it will be evident that the frame members can be straightened out in alinement with each other, with the carrier swinging in a horizontal position therein, as it would be if the form shown in Fig. 2 were merely straightened up to a vertical position. This brings the hand grip 18 on the frame member 12, uppermost, as shown, and in position so that the device can be moved along on the floor or walk, or can be bodily carried, with the two castors, 25, 25, on the floor.

By adjusting said frame members 1 and 2 in alinement with each other, as in Fig. 3, and moving two castors 24, 24 to the lower ends, 12^a and 13^a, the upper end can be held in the hand and the device pushed along on the floor or walk as indicated. An additional flap or seat member, 26, can be buttoned across the lower end of said carrier frame 9, as indicated in Fig. 3, whereby the baby can sit therein, as will be readily understood from the drawing.

Thus many different uses can be made of the device. It will also be evident that it can be set in an automobile and adjusted so as to best fit the space available for it, according to the space in the machine.

I do not limit my invention to the details shown for illustrative purposes, except as I may be limited by the hereto appended claims.

I claim:

1. In a device of the character referred to, a frame hinged at its opposite ends whereby to be folded to different angles, one of said sides having an arm extended therefrom to rest upon the floor when said frame is at rest, and a carrier supported in said frame and adapted to receive articles, substantially as described.

2. A carrier of the character referred to including a rectangular frame of tubular members, the end members being hinged in their middles, locking means at the hinge for locking said end members in different angular positions, one of the side members having an arm extended laterally therefrom to form a support when one of the sides is adjusted with the end members to raised positions, and a carrier supported in said frame to hang freely therein as said frame is adjusted to different forms.

3. A carrier comprising a rectangular frame with its end members hinged, locking means at the hinges to hold them in adjusted positions, a carrier frame pivotally supported therein, carrier means detachably secured to said carrier frame, and castors on said frame, one of said side frame members having a side arm with castor at its end.

4. A carrier of the character referred to, including in combination, two frame members, each having a side and two ends, the ends being at angles to the side members, said ends being hinged together, whereby to form a frame adjustable in its middle portion, with means at the hinges to hold said frame members in angular positions and in the same plane, as desired, a carrier body connected at its opposite ends to said ends at the hinges, whereby the frame members are adjustable around said carrier body, and castors adjustable from the sides of said frame to the ends, whereby said frame in its various adjustments can be moved on castors, substantially as described.

5. A carrier of the character shown and described comprising a frame of tubular members with combination hinges and locks at its opposite ends, whereby the sides of said frame can be adjusted to various positions relative to each other and locked in such adjusted positions, said hinges being such as to permit one side of said frame to be raised above the other side and locked, a carrier body connected at its opposite ends in said frame at the hinges thereof, one of said side frames having a lateral arm projecting therefrom and adapted to rest on the floor, castors on said frame members and said arm, said castors being adjustable from one location to another on said members, substantially as shown and described.

Signed at Los Angeles, Los Angeles County, California, this 24th day of September, 1923.

ERROL W. HAWKINS.
